Primary Examiner—James Gandy*Assistant Examiner*—Linda Brooks*Attorney, Agent, or Firm*—Howrey & Simon[57] **CLAIM**

The ornamental design for a display rack with topper, as shown and described.

DESCRIPTION

FIG. 1 is a perspective view of a display rack with topper showing my new design; and.

FIG. 2 is an enlarged top plan view thereof.

The side of the topper not shown in FIG. 1 is the same as the two sides shown therein.
